SPRING WINDING DEVICE

Charles Hill, Reno, Nev., and Charles K. Johns,
New York, N. Y., assignors to Hil-Jon Safety
Crown Corporation, Brooklyn, N. Y., a corpora-
tion of New York

Application November 27, 1944, Serial No. 565,342

3 Claims. (Cl. 58—83)

1

This invention relates to a winding device and in particular to one made particularly for use in small watches.

A particular object of the invention is to arrange such a device within the crown of a small watch so that a minimum number of parts will be necessary, these parts may be assembled with ease, and can be properly fitted to the minute structure of fine watches where space is at a premium.

Still further objects of the invention reside in the provision of means for preventing overwinding of a watch spring, strain on the main spring, stripping of the winding gears, the rupture of connected parts within the watch and the complete housing of said means within the crown or winding collet which renders the parts dust proof and substantially sealed within the crown without in any way changing the appearance of the watch or necessitating a change in the shape of the crown itself.

Due to the fact that watches for wrist wear, and particularly the type worn by women are of such small dimensions, any conventional de-clutching member cannot be used to disconnect the winding parts and in the present invention we present a novel structure that can be placed inside the hollow crown, can employ a friction disk which may be readily secured to the winding member and one which can be adjustably tensioned to do the work involved in watches of various sizes. The invention does not interfere in any way with the mechanism of the watch and prevents the frequent need of vital repairs.

Still further objects of the invention include the reversibility of the parts for use under different watch structures and conditions; the use of a plate member within the crown whose variation in thickness may be employed to tension the winding friction disk and the means of shaping the friction disk so that varying areas of friction surface may be obtained. Further, is the fact that the winding crown and its means of attachment to the winding shaft of the watch may be made as a unit to be fitted to any watch in use, the crown piece being made up separately. By preventing overwinding of the watch spring the teeth in the main spring barrel and in the center wheel are not damaged and breaking loose of the spring from the barrel is guarded against.

With these and other objects in view, the invention comprises certain constructions herein-after described and then particularly pointed out in the claims, and a preferred embodiment of our invention is illustrated in the accompanying drawing, in which:

2

Figure 1 is a side view of a crown winding device partly shown in section,

Figure 2 is a view of the crown parts of Figure 1,

Figure 3 is a view in section of a crown showing the parts reversed with respect to the crown,

Figure 4 is a section on the line 4—4 of Figure 3,

Figure 5 is a diagrammatic view of part of a friction disk,

Figure 6 is a plan view of another form of the invention,

Figure 7 is a view in sectional elevation of the crown shown in Figure 6.

Referring to the drawing in detail, 10 indicates in outline, the usual winding shaft of a watch through the medium of which the main spring is wound when the crown piece is rotated, the watch structure forming no part of the present invention except as an illustration of the application thereto of our novel winding crown, which is made as a separate unit to be applied to any make of watch, particularly small wrist watches in which the crown must be made extremely small. The winding crown comprises a stem 11 bored or threaded interiorly or exteriorly at its end 12 to be secured to the upper end of the winding shaft 10 of the watch.

Essentially, our invention involves the use of driving and driven elements so arranged within

30 the crown cap that they may be inserted in two different ways, one of which is illustrated in the Figures 1 and 2. This method involves drilling a hole in the crown piece, but the preferred form eliminates the use or rather the necessity of

35 drilling this hole, it being understood that when our device is applied to very small watches, the problem of assembling the parts and drilling, that would weaken them, must be dispensed with. However there are cases in which the form of

40 the invention shown in Figures 1 and 2 is essential and as this type is used in the parent application referred to, its use here being to show the use of reversed construction possible. The stem 11 is provided with an integral driven plate

45 13 having either a single or a number of studs 14 projecting from the upper face thereof, as seen in Figure 1, for engagement with the holes 15 in the friction disk 16, which holes may be in the nature of conical depressions or blank holes if desired. As shown in Figure 2, the holes or

50 depressions 17 may be in the upper face of the driven plate 18 for engagement by the conical projections that are formed adjacent the periphery of the friction disk 19 as at 20.

The parts are housed within the crown 22 which is open at the top and presents an an-

nular shoulder or ledge 23 bordering said opening, which shoulder forms a support for a driving plate 24 which seats on the shoulder and is secured thereto by the peening or burnishing over of the rim edge or flange 25. The opposite side of the crown 22 is provided with a central opening through which the stem 11 depends to be attached to the winding shaft 10. The outer surface of the crown is knurled as at 26 to give the usual finger grip for winding. When the driving plate 24 is seated on the shoulder 23 it tensions the disk 19, to which it is attached as by the rivet 27, so that peripheral friction areas 30 of the friction disk will turn the driven plate 13 to wind the spring of the watch until such time as the wound resistance of the watch spring is greater than the tractive effort exerted by the disk on the plate 13, at which time relative slippage between the disk and the plate will occur and an audible warning will be sounded by the clicking action of the projections and depressions.

The friction disk 19 may be circularly domed as in Figures 1, 2 and 3 or may be diametrically ridged as at 32 in Figure 4, for all the forms of the invention. The friction area as illustrated in Figure 5 diagrammatically, may vary in accordance with the pressure placed on the disk. The tension or temper of the disk is such that while the friction area may have a width A under one condition, it will be increased to provide a greater area B as pressed down the amount B'. The difference in the friction driving force can be varied by adjusting the thickness of the driven plate.

In Figures 3 and 4, the crown 35 is closed on top as at 36 and open at the bottom. The crown is closed by a keeper plate 37 which is force fitted or otherwise secured in place on an annular seat 38 formed in the open bottom side of the crown 35. The keeper plate is provided with a central opening 39 through which extends the stem 40 of the driven plate 41, the latter coacting with a friction disk 42 which is secured to the closed top 36 of the crown by the headed end of a rivet projection 43 formed integrally with the crown 35. The cooperating projections 44 of the disk and seats 45 of the plate provide the warning click when the watch spring is wound. While the warning is audible, sensitive fingers can feel the clicking action of the parts, through the gripping contact of the fingers on the crown. The crown 35 is the driving element in this form of the invention or rather it actuates the friction disk directly and not through any intermediate plate member, and does not have an extra drilled hole for the passage of the stem 40.

In the form of the invention as shown in Figures 6 and 7, the crown 60 has a central opening in the bottom thereof as at 61 through which extends the stem 62 of the driven plate 63, which rests in the bottom of the crown and presents opposite flat portions or edges 64 and opposite arcuate edges 65 for engagement with a substantially circular shaped spring 66 of spring wire whose ends are held in suitable openings 67 of the side wall of the crown, so that in winding up the spring of the watch, the parts will have the positions shown in full lines in Figure 6, but when the watch spring is fully wound, the resistance thereof will cause the yield of the spring 66 to permit a stationary position of the plate 63 as illustrated in outline at 68, while the winding movements of the crown and spring con-

5 tinue as permitted by the slight distortion of the spring 66. The plate 63 is held in position against the bottom of the crown by a keeper plate 69 whose bevelled edge 70 is engaged by the peened over rim of the crown as at 71 to hold the keeper plate on the shoulder 72 provided therefor in the upper edge of the crown. In this form of the invention the parts may be reversed to occupy the same relative positions that the parts occupy in Figure 3, that is with the crown inverted and closed at the top and the keeper plate 69 provided with a hole to permit passage of the stem 62. The crown is in the shape of a hollow cup, and when the closure plate is put on the crown it places the disk under tension.

It is evident therefore that we have provided a winding crown construction that may be built into watches during their manufacture or may be manufactured as separate units for fitting or replacement on any make of watch.

Our invention is not to be restricted to the precise details of construction shown since various changes and modifications may be made therein without departing from the scope of the invention or sacrificing the advantages derived from its use.

This application is a continuation-in-part of our application Serial Number 499,234, filed August 19, 1943, for Spring Winding Device, now

30 abandoned.

What we claim is:

1. In a spring actuated device, the combination with a stem operable to wind said spring, of a sleeve member attachable to the stem and presenting an integral driven plate portion, a winding crown cup member having an opening at one side through which said sleeve member extends, an annular shoulder and a flange formed in the opposite side of said cup member, a driving plate arranged to rest on said annular shoulder and be secured thereto by the flange when the latter is turned inwardly, a friction disk fitting within said crown member, means for securing said disk to said driving plate, the disk being arranged for frictional engagement with said driven plate, and said disk having a central depressed portion and being tempered to provide a flat friction driving surface adjacent its periphery for yieldable driving engagement with said driven plate portion.

2. In a spring actuated device, the combination with a stem operable to wind said spring, of a sleeve member attachable to the stem and presenting an integral driven plate portion, a winding crown cup member having an opening at one side through which said sleeve member extends, an annular shoulder and a flange formed in the opposite side of said cup member, a driving plate arranged to rest on said annular shoulder, means for securing said plate to said crown cup member, a friction disk fitting within said crown cup member, means for securing the disk to said driving plate, the disk being arranged for frictional engagement with said driven plate, and said disk having a central depressed portion and being tempered to provide a flat friction driving surface adjacent its peripheral edge for yieldable driving engagement with said driven plate portion.

3. In a spring actuated device, the combination with a stem operable to wind said spring, of a sleeve member attachable to the stem and presenting an integral driven plate portion, a winding crown cup member having an opening at one side thereof through which said sleeve member

extends, an annular shoulder and flange formed in the opposite side of said cup member, a driving plate arranged to rest on said shoulder, means for securing said plate to the crown cup member, a friction disk fitting within said crown cup member means for securing the disk to said driving plate, the disk being arranged for frictional engagement with said driven plate, said disk having a central depressed portion and being tempered to provide a flat friction driving surface adjacent its peripheral edge for yieldable driving engagement with said driven plate portion, and coacting detent means in the driving surface of said friction disk and in said driven plate portion.
